UNITED STATES PATENT OFFICE.

ANDERS BORCH RECK, OF HELLERUP, DENMARK.

HOT-WATER HEATING APPARATUS.

SPECIFICATION forming part of Letters Patent No. 777,308, dated December 13, 1904.

Application filed July 6, 1904. Serial No. 215,528. (No model.)

To all whom it may concern:

Be it known that I, ANDERS BORCH RECK, captain, a subject of the King of Denmark, residing at 16 Christiansvej, Hellerup, in the 5 Kingdom of Denmark, have invented new and useful Improvements in Hot-Water Heating Apparatus, of which the following is a specification.

In that kind of hot-water heating apparatus 10 in which the velocity of the water through the pipes is increased through the development or the introduction of steam in the main rising-pipe the water in leaving the latter will have the temperature of the steam, whereas, especially 15 in mild weather, a lower temperature may be desirable in the radiators of the heating apparatus. Even when the velocity of the water is increased by other means than development of steam in the main rising-pipe—as, for instance, by the application of injectors or 20 pumps—it may be desirable to lower the temperature of the water as it leaves the injector or the pump.

The subject of the present invention is an 25 arrangement whereby the temperature of the water in a central place just as it leaves the main rising-pipe or the pump can be regulated to that best suitable to the circumstances.

The accompanying drawing illustrates dia- 30 grammatically, as an example, one form of carrying out the invention.

E is a low-pressure steam-boiler in which a 35 constant pressure can be kept in well-known manner by a draft-regulator actuated by the pressure of the steam in the boiler.

s is a steam-pipe that connects the boiler with a perforated tube in a receptacle H, (the heater,) which is inserted in the main rising-pipe N of a hot-water heating apparatus.

40 A pipe M, that is the uppermost part of the main rising-pipe, connects the heater H with the expansion-tank S. From the upper part of the tank S an overflow-pipe f leads to the condenser C, formed as a jacket around the 45 main rising-pipe N, and, further, on to the water-space of the boiler. From the lower part of the expansion-tank S the pipe N' conducts away the heated water. On the condenser C is placed an automatic air-valve I, that keeps 50 open till the interior of the condenser is filled

by steam, when it closes automatically, preventing the escape of steam.

When steam generated in the boiler penetrates into the heater H through the perforated pipe, the water in the heater boils, and consequently when the water rises to the expansion-tank S through the pipe M it is mixed with steam-bubbles. The specific gravity of this current being very low, the velocity of the water first through the pipe M and then 60 through all the pipes of the whole heating apparatus will be greatly increased. In this manner the water is heated at the same time it is put in motion. The steam that rises with the water into the tank S passes through the 65 pipe f to the condenser C. Here it is condensed and finds its way back to the boiler, together with the water that overflows from the tank S through the pipe f. The foregoing arrangement of apparatus is well known 70 and forms no part of this invention. It is only described to show one kind of apparatus to which the invention can be applied with advantage.

Now it will be seen from the drawing that 75 the pipe N', through which the heated water leaves the expansion-tank, is provided with a regulating-valve A and connected with the pipe N², which leads to the radiators at a point where connection is also made between the 80 pipe N² and the short pipe N⁴. The pipe N⁴, which is provided with a valve B, is connected at its other end to the pipe N³, through which the cooled water leaves the radiators at the point where the pipe N³ is connected with 85 the pipe N, that leads to the heater H. It will be seen that if the valve B is shut while the valve A is kept open the water will pass to the radiators through the pipes N' and N² at the same temperature with which it leaves 90 the tank E; but if the valve B is opened and the valve A is closed partially the effect will be as follows: Because the valve A is only partly open the water flowing past it in pipe N' will not be sufficient to wholly fill the riser 95 N², and when the current of water in the return-pipe N³ reaches the point where that pipe is connected with the two pipes N and N⁴ the current will divide itself, part going to the heater H, but the rest passing through the 100

pipe N^4 and the valve B to the pipe N^2 , where, as described above, it is mingled with heated water arriving through pipe N' . By closing the valve A in pipe N' , more or less, it is possible in this manner to lower the temperature of the water passing through pipe N^2 to the radiators as much as desired below the temperature existing in pipe N' .

Having now described my invention, what I claim as new, and desire to secure by Letters Patent, is—

In a hot-water heating apparatus with means for increasing the velocity of the water

the combination of a continuous hot-water heating-circuit, a heater H inserted in said circuit, a pipe N^4 connecting the main return-pipe of said circuit with the main flow-pipe as a by-pass short-circuiting the heater, a valve B on the by-pass and a regulating-valve A controlling the flow of water through the heater. 15 20

In witness whereof I have hereunto set my hand in presence of two witnesses.

ANDERS BORCH RECK.
